SIDNEY W. FARNSWORTH, OF PITTSBURGH, PENNSYLVANIA, ASSIGNOR TO WESTINGHOUSE ELECTRIC AND MANUFACTURING COMPANY, A CORPORATION OF PENNSYLVANIA.

SHIELDING SYSTEM FOR VAPOR-CONVERTERS.

1,232,470.

Specification of Letters Patent. Patented July 3, 1917.

Application filed August 9, 1915. Serial No. 44,429.

To all whom it may concern:

Be it known that I, SIDNEY W. FARNSWORTH, a citizen of the United States, and a resident of Pittsburgh, in the county of Allegheny and State of Pennsylvania, have invented a new and useful Improvement in Shielding Systems for Vapor-Converters, of which the following is a specification.

My invention relates to shielding systems for vapor converters, and it has for its object to provide means that shall minimize short circuiting and reverse arcing and otherwise improve the operation in apparatus of the character indicated.

In the accompanying drawing, Figure 1 is a side view, partially in elevation and partially in section, of a vapor converter embodying two forms of my invention; and Fig. 2 is a side view, partially in elevation and partially in section, of a vapor converter embodying still another form of my invention.

In the operation of vapor converters and similar evacuated electric apparatus, current is, in general, conveyed between the electrodes by a stream of negative electrons emitted by the cathode and proceeding to the anode. The stream of electrons at the cathode may be excited by any of several well known methods, chief among which are the maintenance of a keep-alive arc to the cathode, the maintenance of the cathode at incandescence, the impact of a stream of positive ions thereagainst, and the impact of a beam of ultra-violet light.

If, in its passage from the cathode to an anode, an electron collides with a particle of residual gas, the particle is broken up into a positive ion and a negative electron, both of which receive an initial impulse toward the anode by the impact. The newly freed negative electron moves on very rapidly because the propelling force of the electrostatic field is substantially coincident in direction with the initial impulse thus given, but the newly freed positive ion moves but slowly and may soon come to rest and even reverse its direction of movement because of the neutralizing influence of the electrostatic field upon the initial impulse. Furthermore, the acceleration tending to be imparted to the positive ion by the electrostatic field is much less than that of the negative electron because of the vastly larger mass of the former, although carrying an

equal charge. The delivery of a glancing blow to a gas particle by an electron may disrupt the particle and force the resultant masses more or less transversely to the arc path into comparatively weak fields of electrostatic force.

The passage of an anode to a condition of negative polarity with respect to the cathode, such as happens periodically in a vapor converter, finds a large number of free positive ions afloat in and near the arc path without any well defined motion in any direction. These "tramp" ions are now attracted to the temporarily negative anode and, if in sufficient number and sufficiently accelerated, they may bombard the electrode so energetically as to break down the negative electrode reluctance thereof, causing short circuiting or reverse arcing within the apparatus. This harmful action is especially liable to take place if the positive ions impinge upon a globule of mercury or other foreign matter upon the electrode surface.

By my invention, I mount conducting members adjacent to electrodes subject to the above described action and I charge said conducting members to such polarities that the said action is greatly reduced in intensity.

Referring to the accompanying drawing for a more detailed understanding of my invention, I show a vapor converter at 3 in Fig. 1, provided with solid anodes 4 and 5 and with a cathode 6, preferably composed of vaporizable reconstructing material, such as, for example, as mercury or suitable amalgams. The two anodes 4 and 5 are connected, respectively, to the terminals of the secondary winding of a transformer 7, and the cathode 6 is connected to the mid point of said secondary winding through a load 8, as is customary in rectifier systems. The negative-electrode reluctance of the cathode 6 may be maintained in a broken-down condition by any suitable means, such, for example, as a keep-alive circuit 9. The anode 4 is surrounded by a metallic casing 10 provided with a transverse diaphragm 11 at its lower end. The diaphragm 11 is provided with a plurality of openings wherein are mounted short lengths of tubing 12—12 formed of conducting material. An insulating member 13, mounted upon the member 10, carries a conducting plate 14 in which are mounted tubular members 15 similar to

the members 12 and preferably arranged in staggered relation thereto. The anode 4 is connected to the casing 10 through a resistance member 16 and, in like manner, the diaphragm 11 is connected to the plate 15 through a resistance member 17.

When the anode 4 is temporarily positive with respect to the cathode 6, a stream of negative electrons emitted from the latter 10 passes through the tubular members 12 and 15 to the anode, being brought into very intimate contact with the conducting shielding system because of the small size and large number of tubular members. As the 15 anode 4 passes the crest of its activity and its positive polarity diminishes, a large number of free positive ions, which have been produced by the shattering of gas particles, collect in the arc path. When the anode 4 20 becomes negative in polarity, said free positive ions would be drawn thereto, with the possible production of a cathode spot, were it not for the fact that they are brought into intimate contact with the conducting shielding system, which is, at the same instant, 25 also negative in polarity. The said positive ions are therefore collapsed upon the members 12 and 15, rather than upon the anode itself, and no destructive arc is produced 30 thereby because of the choking effect of the resistance members 16 and 17.

When positive ions are being collapsed upon the tubular members 12 and 15, a small current is set up which results in potential 35 drop in the resistance members 16 and 17. The fact that a greater total resistance is included between the plate 14 and the anode 40 than between the diaphragm 12 and the anode 4 results in a greater difference of potential and, consequently, the plate 14 is nearer in potential to the cathode 6 than is the diaphragm 12. It follows, therefore, 45 that there are no extremely steep potential gradients within the container such as would result in possible harmful effects on the operation of the apparatus.

I show a shielding system associated with the anode 5 in Fig. 1 which is essentially the same in theory and operation as that 50 shown in connection with the anode 4, although operating in a more satisfactory manner because of differences in details of construction. A casing 10 surrounding the anode 5 is provided with a pair of transverse 55 diaphragms 18 and 19 at the lower end thereof. The diaphragm 18 supports a plurality of conducting tubular members 20-20 and the diaphragm 19 supports a plurality of similar members 23-23. The tubes 60 20-20 are preferably arranged in staggered relation to the tubes 23-23 and all of said members are insulated by bushings 21-21.

The tubular members 23-23 are connected to the anode 5 through a resistance device 65 22, and the members 20-20 are connected

to an intermediate point in the device 22 so that a gradual potential gradient is maintained in a manner similar to that shown in connection with the anode 4.

Referring to Fig. 2, I show an anode 30 mounted within a container 3 in operative relation to a cathode 6. An anode shield 24 is provided with two transverse insulating diaphragms 25 and 26 which, in turn, support conducting tubular members 27 and 28, 75 preferably mounted in staggered relation with respect to each other. The tubular members 28 are connected to the anode 23 through a resistance member 29, and the tubular members 27-27 are connected to 80 an intermediate point in the resistance member 29, so that the two sets of tubular members are maintained at slightly different potentials, in a manner similar to that shown in connection with the anode 5 in Fig. 1. 85

If it be desired to obtain an even more complete neutralization of the positive space charge and a more gradual potential gradient, the anode may be protected by more than two groups of collapsing tubes, and 90 various other expedients may be resorted to for obtaining a more intimate contact between the arc and the collapsing apparatus.

I am aware of U. S. Patent #1,110,600, issued to Percy H. Thomas on Sept. 15, 1914, and disclosing a structure somewhat similar to mine but my improvement there-over lies in the specific methods employed to associate the suppressor members with the anodes and in the employment of a plurality 100 of suppressor members of different potential with each anode, whereby steep potential gradients are avoided. This last named feature in my device amounts to more than mere duplication of the Thomas shield because, at voltages higher than a certain minimum, it is difficult to obtain satisfactory operation with a single shield, whereas, by multiplying the number of shields in accordance with the operating voltage 110 and by maintaining an even gradation of potential therethrough, satisfactory operation may be secured at any desired voltage. 105

Furthermore, in the apparatus of Thomas, it is necessary to employ a throat member 115 of comparatively large cross section in order that an undue constriction be not imposed upon the power arc, such as would result in a radical increase of the resistance of the arc path. A throat member sufficiently 120 large to comply with this condition, in a commercial converter, would be so large that many positive "tramp" ions would be able to pass therethrough, even in spite of the electrostatic charge on said throat member. With the construction which I have disclosed, however, the arc is forced to traverse a large number of throat members, each of comparatively small cross sectional area. By providing a sufficiently large number of 125 130

such throat members, no constricting influence is imposed upon the arc but, nevertheless, all portions of the arc are caused to pass extremely close to an electrostatically charged wall. The main free path of the positive tramp ions between successive impacts is fairly large and said ions therefore describe a zig-zag course as they move toward the temporarily negative anode. Said zig-zag course appears to lead, in substantially all cases, into such operative proximity to the wall of a throat member that the electrostatic attraction of said wall overcomes the inertia of the positive tramp ion, collapsing the same and preventing its passage to the anode.

Throughout this description, I have explained the action of my device in accordance with the theory which seems most plausible in view of the present knowledge of the underlying phenomena. I desire it to be distinctly understood, however, that I do not confine myself to said theory of operation but merely present the same to aid in an understanding of the invention.

While I have shown my invention in its preferred form, it will be obvious to those skilled in the art that it is susceptible of various minor changes and modifications without departing from the spirit thereof, and I desire, therefore, that no limitations shall be placed thereupon except such as are imposed by the prior art or are specifically set forth in the appended claims.

35 I claim as my invention:

1. In a vacuum-type converter, the combination with an electrode, of a shielding member surrounding said electrode and provided with a tubular, conducting, arc-admitting member, and a conducting connection from said tubular member to a source of potential of like polarity to said electrode, the diameter of the arc-admitting opening being so small as to cause substantially all the positive "tramp" ions to come within the electrostatic influence of the walls thereof.

2. In a vacuum-type converter, the combination with an electrode, of a shielding member surrounding said electrode and provided with a tubular, conducting, arc-admitting member, and a conducting connection from said tubular member to said electrode, the diameter of the arc-admitting opening being so small and the length thereof being so great that substantially all the positive "tramp" ions come within the electrostatic influence of the walls thereof in attempting to traverse said opening.

60 3. In a vacuum-type converter, the combination with an electrode, of a shielding member surrounding said electrode and provided with a tubular, conducting, arc-admitting member, a conducting connection from said tubular member to said electrode,

and a current-limiting device in said connection, the diameter of the arc-admitting opening being so small and the length of said opening being so great that one of the mean free paths of substantially every positive "tramp" ion attempting to traverse said opening leads into such proximity to a wall of said opening as to cause said ion to be held by said wall.

4. In a vacuum-type converter, the combination with an anode which is periodically negative in polarity, of a shielding member surrounding said anode and provided with a tubular, conducting, arc-admitting member, and a conducting connection from said tubular member to a source of potential of like polarity to said anode, the diameter of the arc-admitting opening being so small as to cause substantially all the positive "tramp" ions to come within the electrostatic influence of the walls thereof.

5. In a vacuum-type converter, the combination with an anode which is periodically negative in polarity, of a shielding member surrounding said anode and provided with a tubular, conducting, arc-admitting member, and a conducting connection from said tubular member to said anode, the diameter of the arc-admitting opening being so small and the length thereof being so great that substantially all the positive "tramp" ions come within the electrostatic influence of the walls thereof in attempting to traverse said opening.

6. In a vacuum-type converter, the combination with an anode which is periodically negative in polarity, of a shielding member surrounding said anode and provided with a tubular, conducting, arc-admitting member, a conducting connection from said tubular member to said anode, and a current-limiting device in said connection, the diameter of the arc-admitting opening being so small and the length of said opening being so great that one of the mean free paths of substantially every positive "tramp" ion attempting to traverse said opening leads into such proximity to a wall of said opening as to cause said ion to be held by said wall.

7. In a vacuum-type converter, the combination with an anode, of a shielding member surrounding said anode and provided with an insulated, tubular, conducting, arc-admitting member, and a connection from said tubular member to a source of potential varying in synchronism with the potential of said anode, the diameter of the arc-admitting opening being so small as to cause substantially all the positive "tramp" ions to come within the electrostatic influence of the walls thereof.

8. In a vacuum-type converter, the combination with an anode, of a shielding member surrounding said anode, and provided

- with a plurality of insulated, tubular, conducting, arc-admitting members arranged so that the arc passes through them in succession, and connections from said tubular members to said anode, the tubular openings in each of said members being so small and of such length that substantially all positive "tramp" ions, in attempting to pass therethrough, come within the electrostatic influence of the walls thereof.
5. In a vacuum-type converter, the combination with an anode, of a shielding member surrounding said anode and provided with a plurality of insulated tubular conducting arc-admitting members so arranged that the arc passes through them in succession, a connection from said anode to each of said tubular members, a resistance member inserted in one of said connections, 10 and a resistance member of different value inserted in the other connection.
6. In a vacuum-type converter, the combination with an anode, of a shielding member surrounding said anode and provided with a plurality of insulated tubular conducting arc-admitting members arranged so that the arc passes through them in succession, a connection from said anode to each of said tubular members, a resistance member inserted in the connection to the tubular member nearest to the anode, and a resistance member of greater value inserted in the connection to the other tubular member.
7. In a vacuum-type converter, the combination with an anode, of a shielding member surrounding said anode and provided with a group of tubular conducting arc-admitting members, a second group of similar arc-admitting members disposed at a different point in the arc stream, and connections including current-limiting devices from said anode to said groups of tubular members.
8. In a vacuum-type converter, the combination with an anode, of a shielding member surrounding said anode and provided with a group of tubular conducting arc-admitting members, a second group of similar arc-admitting members disposed at a different point in the arc stream, connections including a resistance member from said anode to the group disposed nearer thereto in the arc stream, and a connection including a resistance member of greater value between 40 said anode and the remaining group.
9. In a vacuum-type converter, the combination with an anode, of a shielding member surrounding said anode and provided with a plurality of groups of tubular conducting arc-admitting members mounted between said electrodes so that said arc passes therethrough in succession, and conducting connections between said conducting members and one of said electrodes, the openings in each of said members being so small and of such length
- 10 that substantially all positive "tramp" ions, in attempting to pass therethrough, come within the electrostatic influence of the walls thereof.
14. In a vacuum-type converter, the combination with a pair of electrodes, of means for initiating and maintaining an arc therebetween, a plurality of perforated conducting members mounted between said electrodes so that said arc passes therethrough 70 in succession, and conducting connections, including resistance members, between said conducting members and one of said electrodes, the opening in each of said members being so small and of such length that substantially all positive "tramp" ions, in attempting to pass therethrough, come within the electrostatic influence of the walls thereof.
15. In a vacuum-type converter, the combination with a pair of electrodes, of means for initiating and maintaining an arc therebetween, a plurality of groups of tubular conducting members mounted between said electrodes so that said arc passes therethrough 75 in succession, and conducting connections including resistors between said conducting members and one of said electrodes, the connection to the group nearest said electrode in the arc path having a minimum resistance 80 and the groups mounted at greater distances having correspondingly greater resistances in the connections thereto.
16. In a vacuum-type converter, the combination with an anode which is periodically negative in polarity, of a shielding member therefor provided with a plurality of perforations, a tubular, conducting, lining member mounted in each of said perforations, and means tending to impart a negative charge to said lining members at all times when said anode is negative in polarity, the joint cross-section of the openings through said lining members being sufficiently large 90 to produce substantially no diminution in the cross-section of a power-arc operating to said anode, and the cross-section of the opening through each lining member being so small and the length thereof so great that substantially all positive "tramp" ions attempting to pass therethrough come within the electrostatic influence of the walls thereof.
17. In a vacuum-type converter, the combination with an anode which is periodically negative in polarity, of a shielding member therefor provided with a laminated wall portion, the laminations of said wall portion being spaced apart and being provided with perforations, a tubular, conducting lining member mounted in each of said perforations, and means tending to impart a negative charge to said lining members at all times when said anode is negative in polarity, the joint cross-section of the openings 100
- 110
- 115
- 120
- 125
- 130

through said lining members being sufficiently large to produce substantially no diminution in the cross-section of a power-arc operating to said anode, and the cross-
5 section of the opening through each lining member being so small and the length thereof of so great that substantially all positive "tramp" ions attempting to pass there-
through come within the electrostatic influ-
10 ence of the walls thereof.

18. In a vacuum-type converter, the combination with an anode which is periodically negative in polarity, of a shielding member therefor provided with a laminated wall
15 portion, the laminations of said wall portion being spaced apart and being provided with perforations, a tubular, conducting lining member mounted in each of said perforations, means tending to impart a nega-
20 tive charge to the lining members mounted in the wall lamination nearest the anode at

all times when said anode is negative in potential, means tending to impart successively smaller and smaller negative charges to the lining members mounted in the laminations 25 through said lining members being sufficiently large to produce substantially no 30 diminution in the cross-section of a power-arc operating to said anode, and the cross-
35 section of the opening through each lining member being so small and the length thereof of so great that substantially all positive "tramp" ions attempting to pass there-
through come within the electrostatic influence of the walls thereof.

In testimony whereof, I have hereunto
subscribed my name this 30th day of July 40
1915.

SIDNEY W. FARNSWORTH.
